METHOD AND MEANS FOR CLEANING MEAT STUFFERS

Filed May 13, 1926

UNITED STATES PATENT OFFICE.

GEORGE R. NAPIER, OF CLEVELAND, OHIO.

METHOD AND MEANS FOR CLEANING MEAT STUFFERS.

Application filed May 13, 1926. Serial No. 108,734.

This invention relates to the art of stuffing meat. In particular it is concerned with a new and improved method of and means for cleaning meat stuffers having meat-expelling pistons operated by compressed air or other gas.

An important object of the invention is to provide a simple and efficient method of and means for cleaning the space behind the piston of a stuffer of the described type.

Meat stuffers having a meat-expelling piston operated by air or other gas under pressure have been in use for many years and have possessed the serious disadvantage of leakage of meat past the piston into the space therebehind and accumulation therein in quantities which rendered the stuffer unsanitary, unless such accumulation is removed before decomposition begins. The only methods of cleaning such space, as practiced heretofore, so far as I am aware, have been to remove a hand-hold cover and scrape out the accumulated meat, or to take the heavy piston from the cylinder and then scrape out the space. Each method requires considerable time and labor and does not permit of the desired thoroughness of cleansing.

My invention, however, requires but little, if any, additional simple apparatus and can be carried out in a few minutes without dismantling the stuffer or its parts. Moreover, it cleanses the said space thoroughly and is so simple and easy to practice that it may be used daily, thus not only insuring perfect sanitation at all times but also preventing spoilage losses and permitting the production of high-grade meat.

In the figures attached hereto and forming a part of this specification in which one form of apparatus embodying my invention is illustrated—

Fig. 1 is a vertical sectional view of a stuffer and associated parts constructed in accordance with my invention;

Fig. 2 is a side elevation of a similar stuffer associated with a modified form of apparatus; and

Figs. 3 and 4 are fragmentary views showing still other modified forms of apparatus with which my invention may be practiced.

In the figures, the meat stuffer shown comprises a cylinder 1 closed at one end by a removable cover 2 and at the other end by a fixed end 3. One or more tubes 4 near cover 2 form outlets through which meat may be forced from the cylinder 1. A piston

5, reciprocable in the cylinder, serves to force the meat out through tubes 4, when air or other compressed gas is lead into the chamber or space 6 in the cylinder behind the piston and between piston 5 and end 3. A pipe 7, connected to a source of compressed gas (not shown), opens into the space 6 to lead the gas thereinto. A three way valve 8 is shown in the pipe 7 with an exhaust opening at 9. If desired, a bent pipe 10 may be extended from pipe 7 down close to the end wall 3, for a purpose presently to appear.

In Fig. 1, I have shown a pipe or hose 11 connected to the exhaust opening 9 of valve 8 and to a pump 12, the inlet side of the pump being connected to a reservoir 13 for liquid, for example hot water with or without cleaning substances therein.

In Fig. 2 I have shown a reservoir 14 corresponding to reservoir 13, mounted on a wheel carriage 15 and carrying a motor 16 to drive a pump 17 with which a hose 18 similar to hose 11 may be coupled.

In Fig. 3 I have shown a water main 19 so arranged adjacent to wall 20 and having a valve 21 and a pipe or hose 22 joining the valve to the exhaust opening 9 of valve 8.

In Fig. 4 I have shown a stuffer 1 fitted with a valve 23 which opens into the space 6 behind the piston, and which serves as a means by which liquid may be brought into or discharged from the space 6 behind the piston. It will be obvious to those skilled in the art that connections with this valve may be made from either of the types of pumps shown in Figs. 1 and 2, or from the water line 19, such as is shown in Fig. 3. It will also be obvious that more than one valve 23 may be used if desired, for example one to serve as a water inlet and the other to serve as a water outlet from the space 6. A valve 25 is provided to permit the escape of air from the space 6, and to insure cleaning contact of the cleaning liquid with the lower surface of the piston when the cleaning is accomplished, without the introduction of compressed gas through the liquid in the space.

When it is desired to remove meat, refuse and the like from space 6 and to cleanse, sterilize and rinse the space or chamber, the cover 2 is preferably clamped in place and tubes 4 closed. Pipes 11, 18 or 22 are connected to the exhaust outlet of valve 8 or to valve 23, and cleaning liquid is delivered into space 6, enough force being used for this

purpose to overcome any back pressure caused by air in the space, and preferably enough additional force is used to move the piston toward cover 3. Then the valve 8 5 is turned to admit compressed gas into space 6, as much being admitted as may be desired, for example up to 100 lbs. pressure per square inch or until piston 5 is moved close to cover 2, or both. Such gas will pass up through 10 the liquid in bubbles and will thoroughly agitate the liquid thereby stirring up meat lodged in corners of the chamber and causing 15 it to be suspended in the liquid and bringing the liquid into cleaning contact with the lower surface of the piston. When there is sufficient pressure on the liquid, the pipe 13, 18 or 22 is detached, preferably from pumps 12, 17, or valve 21, as the case may be, the end being placed in or over a suitable 20 receptacle to receive the expelled liquid, and then valve 8 is turned to connect space 6 with outlet opening 9, whereupon the liquid and meat in the space will be forcibly discharged through pipe 13 or 18. With the arrangement 25 of Fig. 1, pipe 11 need not be disconnected but by opening valve 24 an outlet for the liquid will be provided.

More than one method of practicing my invention may be carried out by the apparatus of Fig. 4. For example, cleaning liquid may be brought into the space 6 30 through pipe 7 and discharged through valve 23 or pipe 7 as desired. The cleaning liquid may also be brought into and discharged from the space 6 through valve 23. Compressed gas may be used regardless of 35 the particular method of bringing liquid into space 6 of Fig. 4 and discharging it therefrom. Moreover, the use of compressed gas 40 is not essential with this particular modification of apparatus. The valve 25, if opened during the entry of fluid into the space 6, will permit escape of air or gas therefrom and insure substantially complete filling of 45 the space with liquid, so that the liquid will come into cleaning contact with the lower surface of the piston and not be separated therefrom by a substantially insulating layer 50 of compressed gas, as would otherwise be the case. When the valve 25 is used in this manner it may be closed when the space 6 is completely filled to permit the cleaning fluid to remain in contact with the walls of space 6, but when it is desired to withdraw the liquid 55 from space 6 the valve 25 is opened, the liquid escaping through valve 23.

When curved extension 12 is used, nearly or practically all the liquid may be exhausted from the space 6. If any cannot be so removed and it be desirable to remove it, a suitable plugged drain hole 26 may be utilized.

I have found that the walls of space 6 60 may be rendered substantially dry and more or less thoroughly protected from rusting if,

after the cleaning and rinsing fluids have been withdrawn from the space, compressed gas is admitted to the space and then exhausted therefrom one or more times. Such gas has the effect of blowing out or carrying out with it the remaining traces of moisture and liquid.

Various other means of introducing liquid into the space behind the stuffer and removing it therefrom may be utilized when desired without departing from the spirit of my invention.

It will be observed that I have provided a simple, effective method of thoroughly cleaning stuffing machines to replace the slow, 30 costly, ineffective method practiced for many years heretofore. It will also be observed that I employ little apparatus additional to the stuffer and its parts, but that I utilize parts of the stuffer in a new manner.

Many changes in the apparatus described above may be made without departing from the spirit of my invention, the scope of which is defined in what is claimed.

What is claimed is:

1. The combination with a meat stuffer having a reciprocable meat-expelling piston, of pressure means for introducing cleaning liquid into the stuffer behind the piston and pressure means for removing the said liquid and foreign material forcibly therefrom.

2. The combination of a meat stuffer having a reciprocable piston and a space therebehind, of valve means for controllably admitting cleaning liquid into said space, and pneumatic means for expelling foreign material and the liquid therefrom.

3. The combination with a meat stuffer having a reciprocable piston, a space therebehind and pneumatic means admissible to the space for actuating the piston, of a source of cleaning liquid controllably admissible into the said space, and means for utilizing the said pneumatic means in the space to expel the said liquid and foreign material therefrom.

4. The combination with a meat stuffer having a piston, a multi-way valve, a space behind the piston controlled by the said valve, and a source of compressed gas controllably admissible into said space, of a source of cleaning liquid controllably admissible into the said space through the said valve.

5. The combination with a meat stuffer having a piston, a multi-way valve, a space behind the piston controlled by the said valve, and a source of compressed gas controllably admissible into said space, of a source of cleaning liquid controllably admissible into and removable from the said space through the said valve.

6. The combination with a meat stuffer having a piston, a multi-way valve, a space

- behind the piston controlled by the said valve, and a source of compressed gas controllably admissible into said space, of a source of cleaning liquid controllably admissible through and removable from the said space through the exhaust opening of the said valve.
7. In a meat stuffer, the combination of a cylinder having a reciprocable meat expelling piston and a space behind the piston, valve means for controlling the passage of cleaning liquid into and out of the said space, and means for exerting liquid expelling force on liquid in the said space to 15 expel the liquid and foreign material therefrom.
8. In a meat stuffer, the combination of a cylinder having a reciprocable meat expelling piston and a space behind the piston, 20 valve means for controlling the passage of cleaning liquid into and out of the said space, and pressure means for exerting liquid expelling force on liquid in the said space to expel the liquid and foreign material 25 therefrom.
9. In a meat stuffer, the combination of a cylinder having a reciprocable meat expelling piston and a space behind the piston, valve means for controlling the passage of 30 cleaning liquid into and out of the said space, and compressed gas means for exerting liquid expelling force on liquid in the said space to expel the liquid and foreign material therefrom.
- 35 10. The method of cleaning the space behind the piston of a meat stuffer of the compressed gas type which comprises bringing liquid into contact with meat and other foreign material in such space, agitating the liquid by passing compressed gas there- 40 through, imposing pressure on the liquid confined in the said space, and expelling the liquid together with the meat and foreign material from the said space.
- 45 11. The method of cleaning the space behind the piston of a meat stuffer of the compressed gas type which comprises intro- ducing liquid into the said space, imposing pressure on the said liquid and expelling the liquid together with meat and foreign mate- 50 rials from the said space.
12. The method of cleaning the space behind the piston of a meat stuffer of compressed air type which comprises bringing liquid into such space, and then forcibly expelling the liquid together with meat and foreign materials from the said space.
13. The method of cleaning the space behind the piston of a meat stuffer of the compressed air type which comprises bringing liquid into such space, then imposing gas pressure on the liquid in such space, and permitting the compressed gas to expel the liquid and foreign materials from the said space.
14. The method of cleaning the space behind the piston of a meat stuffer of the compressed air type which comprises bringing liquid into such space and into cleaning contact with the lower surface of the piston, 70 and then removing the liquid together with meat and foreign materials from the said space.
15. The combination with a meat stuffer having a reciprocable meat-expelling piston and a space therebehind, of means for introducing liquid into the said space, means for bringing the liquid into cleaning contact with substantially all of the walls of the said space, and means for removing the liquid from the space.
16. The combination with a meat stuffer having a reciprocable meat-expelling piston and a space therebehind, of means including suitable pipes for introducing liquid into the said space and removing it therefrom, and means including a conduit for the conduction of gas for bringing the liquid into cleaning contact with substantially all of the walls of the said space.

In testimony whereof I hereunto affix my signature this 10th day of May, 1926.

GEORGE R. NAPIER.
